KITE

Application filed September 30, 1925. Serial No. 59,533.

This invention relates to improvements in toy kites and it has for its particular objects to provide a structure of the aero-plane type which can be packed within a small compass in a disassembled condition and be placed on sale and be mailed in this condition, and afterwards be easily assembled for use.

These and other objects hereinafter set forth are attained by the means illustrated in the accompanying drawing, in which:

Figure 1 is a perspective view of the improved kite ready for flying;

Figure 2 is a side elevation of the main frame showing the horizontal plane supports in section, and

Figures 3 and 4 are detail views illustrating one of the coupling-sleeves and one of the tension-wire caps respectively.

Similar reference numerals in all of the figures of the drawing designate like parts.

The frame of the kite embodies a main longitudinal rib 10, an upper longitudinal rib 11, two vertical struts 12 and 13, and the transverse plane-supports 14 and 15, the several elements being connected together by metal couplings 16, 17, 18, 19, 20 and 21, a pair of coupling sleeves 22 and 23, all of the couplings being preferably constructed of aluminum. The supporting frame also embodies horizontal supports 24 for the tail planes, and vertical supports 25 for the tail equalizer.

The main rib 10 passes through the couplings 18 and 19, the openings in these couplings to receive the rib 10 being bored at such an angle to mount the couplings on the rib with their upper ends inclining forwardly, so that the vertical struts 12 and 13 will incline forwardly at their upper ends when their lower ends are mounted in the upper ends of the couplings 18 and 19, and this inclined arrangement of the struts 12 and 13 having the couplings 16 and 17 at their upper ends, positions the leading edge of the upper plane slightly in advance of the leading edge of the lower plane.

Both the upper and lower planes are each preferably formed of two fabric sections 26-27, respectively, the sections being provided with open hems at their edges which are adapted to be slipped upon the free ends of the transverse plane supports 14 and 15

after these supports are mounted in the couplings 16, 17, 18 and 19.

Horizontal rib 11 is merely a brace-rod between the front and rear struts and the ends of this brace-rod are fixed in the couplings 16 and 17 in a plane slightly below the plane of the plane-support 14. The plane supports 15 are mounted in the couplings 18 and 19 in a plane slightly lower than is the main rib 10. This main rib 10 is preferably formed of a front and rear section connected together by coupling-sleeve 23, the adjacent ends of the sections being inserted in opposite ends of the coupling-sleeve and secured therein by transverse-pins 28 or other like fastening means. The purpose of forming the main rib in sections, is to provide separate sections which will be substantially the same length of the plane-supports 14 and 15, so that the packing or bundling of the several sticks will be compacted to form a relatively short and neat package.

Tail-plane-supports 24 are mounted in the couplings 20 and 21 in a plane slightly below the plane of the rear section of the main rib 10, and the vertical supports 25 have their upper ends inserted in the lower ends of the couplings 20 and 21 and are secured therein in any suitable manner, preferably with pins or beads. The horizontal tail-planes are preferably formed of two fabric sections 29-29, which are provided with open hems adapted to be slipped upon the projecting ends of the supports 24, in a similar manner as is done with the main-planes 26 and 27. The vertically arranged equalizer 30 of the tail member is also formed of fabric and provided with open hems adapted to be slipped upon the supports 25.

The ribs or supports 14 and 15 are slightly bowed by the tension wires 31, and these tension wires have their ends connected in any suitable manner to metal caps or cups 32 which can be readily slipped upon the free ends of the plane supports or sticks. As shown in the drawing, the leading edge of the upper plane is preferably bowed downwardly by the tension-wire 31' which is in direct opposition to the curve of the rear edge of said top plane, and to retain this wire 31' which is in direct opposition to the curve of the rear edge of said top plane, and

to retain this wire 31' in its correct position, a top stick 33 is provided which is fixed into the upper end of the coupling 16.

Brace guys 34, preferably formed of strong twine or cord, are provided for retaining the planes as taut as possible. One set of these guys 34 is extended from the ends of the front supports or sticks 14 and 15 to the end 35 of the front end of the main rib or stick which is extended a considerable distance beyond and in front of the coupling 18. The rear set of brace-guys 34 is connected between the extreme ends of the rear-supports or sticks 14 and 15 and the coupling-sleeve 23 of the main stick. The ends of all of these brace guys are secured in position by tying or otherwise.

Mounted horizontally in the front coupling 22 is a control stick 36 and which extends a considerable distance on each side of said front coupling. To the free ends of this control stick is secured one end of the belly-bands 37, the other ends of these bands 37 being connected in any suitable manner to one of the rear coupling members, preferably to the member 20, as shown in Figure 1. These belly-bands are preferably slack between their ends, and to them, intermediate their length, is fastened the flying string 38, which is preferably attached to the bands by a knot which will remain in a fixed position when the kite is being flown, but can be slipped back and forth on the bands by force when desired to adjust the position of the flying string, to secure the best results, as is usual in flying kites.

Mounted between the main-planes is a stabilier 40, preferably formed of a sheet of fabric material and is secured in position by attaching its corners by suitable detachable fastening means 41, such as safety pins, to the upper fabric planes 26 at opposite sides of the struts 12 and 13, and extending it from said means downwardly and inwardly, to and beneath the main-stick 10, which holds it in position in a simple manner. This manner of securing this stabilizer in position provides a V-shaped structure whose angles can be changed to suit flying conditions, by simply adjusting the fastening means 41 along the edges of the planes.

The metal coupling members shown in Figures 1, 2 and 3 are shown formed in one piece, but if desired, they can be formed in sections.

It will be understood, that the parts of all of the sticks engaging the coupling members are secured in position by suitable pins or nails, preferably of the brad type, and in such manner that they can be withdrawn to disassemble the parts when desired.

This kite is adapted to be sold in a disassembled condition enclosed in a suitable wrapper, together with instructions showing and describing how it is assembled. It

is obvious that the several parts can be compacted into a relatively small package especially suitable for a mail-order business.

The manner of assembling is as follows:

The sections of the main stick 10 are first connected together by the coupling 23, and the couplings 18, 19, 20 and 21 are then placed thereon. Struts 12 and 13 are now mounted in the couplings 18 and 19, after the sections of the front strut 12 have been connected together by the coupling 22 and the control-stick mounted in said coupling. Next, the couplings 16 and 17 are mounted on the upper ends of the struts 12 and 13 and said couplings are then connected together by the brace-stick 11. The plane-sticks 14, 15 and 24 are next placed in position in their respective couplings, also the sticks 25. The fabric planes are then slipped in position on their respective sticks, and afterwards the tension wires or trusses are placed in position to bow the planes, simply by inserting their caps over the ends of the plane-sticks, and finally the belly-bands and flying string are secured and adjusted to suit flying conditions.

It will be observed that the struts 12 and 13 incline forwardly above the main stick 10, and the supports 25 incline forwardly below the main stick. This arrangement gives the best results.

Having thus described the invention, what is claimed is:

1. A kite of the character described, comprising bi-planes having transverse supports at their edges, a tail member a main frame embodying a single main stick extending longitudinally and centrally the full length of the kite and having a pair of aligned struts extending upwardly therefrom adjacent its front end, and a longitudinally extending brace connecting the upper ends of said struts, a transverse control stick secured to the foremost strut intermediate its length, and metallic coupling members located at the junctions of said transverse supports, struts and longitudinal supporting members.

2. A kite of the character described, comprising bi-planes having transverse supports at their edges, a tail member, a main frame embodying a single main stick extending longitudinally and centrally the full length of the kite and having a pair of aligned struts extending upwardly therefrom adjacent its front end and a longitudinally extending brace connecting the upper ends of said struts, and couplings located at the junctures of the transverse supports, struts and longitudinally extending sticks, said transverse supports being supported midway their length in said couplings on both struts, and the fabric planes of the bi-planes being slidably in position over the free ends of said transverse supports.

3. A kite of the character described, comprising bi-planes having sticks, a tail member, and a main frame for supporting them, said main frame embodying a central main stick, vertical struts extending upwardly therefrom, means for detachably connecting the bi-plane sticks to said main stick and struts, and a fabric stabilizer mounted between said bi-planes and having its free

edges adjustably connected to the longitudinal edges of the upper plane and extending beneath said main stick, whereby the sides of the stabilizer can be shifted to change the angles thereof to suit variable flying conditions. 10
